UNITED STATES PATENT OFFICE.

FREDERICK O. HILFIKER, OF IRONDEQUOIT, NEW YORK, ASSIGNOR TO F. O. HILFIKER CO., OF SYRACUSE, NEW YORK, A CORPORATION OF NEW YORK.

TOILET IMPLEMENT.

1,078,283.

Specification of Letters Patent.

Patented Nov. 11, 1913.

Application filed April 7, 1911. Serial No. 619,518.

To all whom it may concern:

Be it known that I, FREDERICK O. HILFIKER, of Irondequoit, in the county of Monroe and State of New York, have invented 5 certain new and useful Improvements in Toilet Implements; and I do hereby declare the following to be a full, clear, and exact description of the same, reference being had to the accompanying drawings, forming a 10 part of this specification, and to the reference-numerals marked thereon.

My present invention relates to toilet articles and has for its object to provide a simple and efficient spray head for bathing purposes which may be produced at a low cost 15 and offer certain conveniences in use.

To these and other ends the invention consists in certain improvements and combinations of parts all as will be hereinafter more 20 fully described, the novel features being pointed out in the claims at the end of the specification.

In the drawings: Figure 1 is a top plan view of a bath and massage brush constructed 25 in accordance with and illustrating one embodiment of my invention; Fig. 2 is a side elevation; Fig. 3 is a bottom plan view, and Fig. 4 is a central longitudinal section taken substantially on the line 4—4 of Fig. 1.

Similar reference numerals throughout 30 the several figures indicate the same parts.

In the particular embodiment of the invention illustrated, the head 1 is hollow and annular in shape with a flat foraminous bottom face 2 providing a plurality of jet openings 3 that jointly produce a hollow cylindrical stream or spray. A holder 4 is provided for the head which I prefer to form 35 of a continuous strip of round wire 5 that surrounds the same and has its extremities projected in parallel relationship, as shown at 6 in dotted lines in Fig. 1, for the purpose of providing a handle, as will herein-after appear.

45 A convenient means for connecting the holder to the head and one which I prefer to employ, is best shown in Fig. 4, comprising a plurality of clips 7 that may be stamped from sheet material to embody a central aperture 8 that receives the wire 5, and arms 9 and 10. The first mentioned arm extends downwardly and inwardly, as shown, to hook beneath the under face 2 of the head and over the corner presented by 55 the junction of this wall with the peripheral

or side wall 11. The latter is preferably inclined inwardly, as shown, so that when engaged by the other arm 10, extending above the wire 5, the head is prevented from passing through the eye of the holder in either 60 direction, as will be understood.

As before stated, there are a plurality of the clips 7 disposed at intervals about the circumferences of the connected members which positions they may attain by being 65 threaded upon the wire strip after it is formed into an eye and I prefer to provide the holder with a non-abrasive covering 12 that may be constituted by rubber tubing, also threaded on the wire, but which is divided into sections lying between the several clips 7. They operate to hold the clips properly spaced and at the same time provide a buffer that prevents the implement from doing damage or causing any sound 70 when knocked against other objects, such as a bath tub in which the device is used.

The extremities 6 of the wire are preferably fitted into handle members or grips 13 extending parallel with each other and 80 spaced apart and preferably at the inner ends of these grips the ends of the wire holder are connected together by a suitable tie piece 14 which retains the head 1 tightly clamped within the eye of the holder and at the same time provides a fulcrum for the relative movement toward and from each other of the handle grips 13, such a movement of the outer ends of the latter being permitted by the resiliency of the material 85 from which the holder is made.

The head 1 is supplied with water by a preferably flexible rubber tube or pipe 15 that extends parallel with and between the handle grips 13 and has its extremity connected with the head 1 to deliver into the same by a suitable coupling 16 that is preferably of a kind permitting the supply pipe to be disconnected when desired. The free or movable ends of the grips 13 have 90 jaw faces 17 thereon and when it is desired to temporarily cut off the flow through the pipe 15, or at least so diminish it that the jets from the head will be diminished and not scatter the spray during certain manipulations of the implement, the operator simply tightens his grasp and presses the handle members 13 together with the result that the pipe is squeezed between the jaws 17 and constricted in the manner shown in Fig. 3. 110

When the handle members are released they release the pipe, but the resiliency of the wire is such that the grips have sufficient normal rigidity to prevent the supply pipe from being compressed to an effective degree during ordinary manipulations of the implement.

When it is desired to accompany the spraying of the body with a scrubbing action, the head 1 is fitted with a flesh brush or massage element 18 that is seated within the central opening or socket 19 of the head. I prefer to construct this brush of reasonably soft and pliable rubber and cup-shaped, as clearly shown in Fig. 4. The integral rubber bristles 20 project from the under or outer side of the bottom 21 of the cup, while the side wall or rim 22 is thrust within the socket or opening 19 of the head and, as it is compressed when so inserted, its expansive force and the clinging nature of the material causes it to firmly and frictionally grip the walls of the opening with sufficient force to retain the brush in its seat during all ordinary manipulations, though it may be easily and quickly removed with the fingers by compressing it as it is pulled outwardly. The walls of the socket or opening 19 are preferably tapered and the brush is held in the small end so that it will respond with a wedging action upon the exercise of any force tending to pull it from its seat. To make its position even more secure the brush and socket or, at least, the rim or retaining portion of the latter, may be provided with coöperating shoulders 23 and 24, respectively, that engage and interlock, in the manner shown in Fig. 4. The shoulder on the rubber cup also gives greater body to its retaining portion and renders its expansive tendency more effective.

The brush may be inserted from the top or larger side of the opening 19 in the head in the embodiment shown by thrusting it through the latter, bristles first, but ordinarily it may be safely made sufficiently small to insert it from the other side by crowding the flanged portion or rim thereof inwardly. The removability of the brush permits different ones having different characteristics to be interchanged as conditions require, as, for instance, coarse and fine brushes may be provided with each implement. Also, the brush may be discarded if it is wished to use the spray head or other compound instrument to which the brush is fitted alone or the brush may be itself used alone for massage purposes with or without disconnecting the supply pipe from the head in the present embodiment.

Features of the invention disclosed herein such as relate to the brush alone, independently of the specific nature of the holder to which it is attached are not here claimed as

they form the subject matter of a separate divisional application, Serial No. 735,634, filed by me December 9, 1912.

I claim as my invention:

1. The combination with a spray head having a plurality of jet openings therein, of a holder composed of a continuous strip of material surrounding the head, a plurality of clips connecting it therewith at intervals, and a tubular non-abrasive covering for the holder composed of sections arranged between the clips and constituting a buffer.

2. The combination with a spray head having a plurality of jet openings therein, of a holder therefor composed of a continuous strip of material surrounding the head and terminating in end portions forming a handle.

3. The combination with a spray head having a plurality of jet openings therein, of a handle therefor composed of a pair of relatively movable members directly connected thereto and a flexible supply element delivering to the head extending between said members and adapted to be compressed thereby.

4. The combination with a spray head having a plurality of jet openings therein, of a handle therefor composed of a pair of relatively movable substantially parallel members directly connected thereto, a flexible supply pipe extending longitudinally between the members and delivering to the head and jaw faces on the members adapted, when the latter are pressed together, to pinch the supply pipe and cut off the flow therethrough.

5. The combination with a spray head having a plurality of jet openings therein, of a holder composed of a strip of wire surrounding the head and means for connecting the parts together comprising a plurality of clips having apertures through which the wire passes and hooked portions engaging the rim of the head.

6. The combination with a spray head having a plurality of jet openings in its under wall and an inwardly inclined peripheral wall, of a holder composed of a strip of wire surrounding the head and means for connecting the parts together comprising a plurality of clips having apertures through which the wire passes, arms extending downwardly and laterally beneath the bottom wall and arms extending upwardly and inwardly and engaging the peripheral wall.

7. The combination with a spray head, of a holder therefor composed of a continuous strip of material surrounding the head and terminating in relatively movable resilient end portions jointly forming a handle and a flexible supply element delivering to the head extending between said end portions

and adapted to be compressed thereby to affect the flow when the latter are sprung together.

8. The combination with a spray head, of 5 a holder therefor composed of a pair of members having rigid portions fixed to the head and a tie piece rigidly spacing the members adjacent to the head, said members terminating in relatively movable resilient 10 end portions jointly forming a handle, and

a flexible supply element delivering to the head extending between said end portions and adapted to be compressed thereby to affect the flow when the latter are sprung together.

FREDERICK O. HILFIKER.
